RANGE OR STOVE HAVING BURNER CHAMBERS FOR OIL BURNERS

Harry L. Gere, Bayonne, N. J.

Application December 31, 1936, Serial No. 118,485

3 Claims. (Cl. 126—44)

This invention relates to improvements in a range or stove having burner chambers and their appurtenances for oil burners.

The object of the invention is the production of a range or stove having burner chambers and their appurtenances for oil burners, by which the efficiency of the range or stove is enhanced.

The second object of the invention is the production of means wherewith a burner chamber 10 can be easily provided for an ordinary stove, range, furnace or the like.

In the accompanying drawings Fig. 1 represents a section through a range with an exemplification of the invention, as on the line 1, 1 of Fig. 2; Fig. 2 shows a section of Fig. 1 on the line 2, 2, and Fig. 3 indicates a section of Fig. 2 on the line 3, 3.

Referring to the drawings, a range or stove is indicated having the bottom wall 190, the bottom rear wall 191 and the bottom front wall 192 with the opening 193 for the door 194. The upper rear wall is shown at 196. The upper front wall 199 is shown having the opening 200 for the door 201. Side walls for the range or stove are shown at 202 and 203. A water back is indicated at 203a. A flue connection 204 is indicated with the wall 196. The flue connection 204 is open at both ends and extends through the top plate 206 to be described, into the heating chamber 78a, see Fig. 3, to be described. A stove pipe 204a is connected to the upper end of the flue connection 204. A partition wall 204a extends between the walls 191, 196, 192 and 199, the bottom wall 190 and the top wall 60a. The bottom wall 190, the rear wall 191, the front wall 192 and the wall 215, to be described, form a draft chamber 204b.

A door is shown at 205. The top platform of the range or stove is indicated at 200 with the openings 207 for the removable lids 208.

An oven door 212 is provided for an opening in the upper portion of the front wall 199. An inner bottom wall 215 is indicated with the openings 216. The centers of the holes 216 are disposed in a circle. A mounting bracket 220 is indicated with the sleeve 221 and from the opposite sides of the latter extend a pair of arms like 222, one of which is shown. A leveling screw 223 extends through each arm 222 and bears on the bottom wall 190. An arm 225 at right angles to the arms 222 extend from the sleeve 221. A bolt 226 connects the arm 225 and the wall 190. A column 228 extends from the sleeve 221 and its lower end is fastened in place by the screw 229. A sleeve 231 is fastened to about the middle portion of the column 228 by the screw 232. The sleeve 231 supports the wall 215. At the upper

end of the column 228 is indicated a supporting bracket 235 with the sleeve 236. The latter is fastened to the upper end of the column 228 by the screw 238. Burners 125 are bolted to the supporting bracket 235, by means of the bolts 239.

Similar vertical oil pipes 155 and 155a are connected to the bottom wall of each of the burners 125. Piping 245 extends from the pipe 155 and leads to one of the valves of the double supply valve 248. The oil reservoir is shown at 170. The supply pipe from the reservoir 170 is shown at 180 which feeds the double supply valve 248. From the vertical oil pipe 155a extends the piping 250 which leads to the other unit of the double oil supply valve 248. A vent pipe 182a leads from the double oil supply valve 248. The supports for the burners are again shown at 69.

The top wall of the burner chamber 102a is shown at 60a and is supported on the member 66 of the angle shaped supporting ring. The said 20 supporting rings are supported upon the supports 69. To the lower face of the top wall 60a is bolted the T shaped baffle 255, by means of the bolts 256. Removable hoods are each shown having the conical wall 70 with its opening 71. The 25 wall 70 joins with the vertical flange 72, and the juncture of the wall 70 and the flange 72 bears upon the vertical member 65 of the angle shaped supporting ring. The handles for the hoods are shown at 76.

The walls 196, 202, 203, 206 and the door 205 provide the upper heating chamber 78a.

Referring to the drawings, the kerosene flows from the oil reservoir 170 through the supply pipe 180 to the double supply valve 248. Oil flows 35 through the piping 245, the vertical oil pipe 155 to the wicks of the rear oil burner 125 adjacent to the upper rear wall 196. Oil also flows from the double supply valve 248 into the piping 250 which feeds the front oil burner 125 adjacent to the 40 upper front wall 199. The air in the burner chamber 102a is heated by both of the oil burners therein.

Air is fed to the burner chamber 102a through the openings 216 in the inner bottom wall 215, for 45 the burners.

The walls of the burner chamber 102a maintain the heat of the burners within the same. The T shaped baffle maintains the flames from each of the burners within its own zone. The 50 discharge openings 71 of the removable hoods function as passages for the products of combustion to the upper heating chamber 78a, in which they are confined until they escape through the flue connection 204.

The products of combustion of the heating chamber 78a, escape through the lower open end of the flue connection 204 and the stove pipe 204a.

5 Various modifications may be made in the invention and the present exemplification is to be taken as illustrative and not limitative thereof.

Having described my invention, I claim:

1. In a range or stove comprising a front wall, 10 upper front wall, a rear wall, an upper rear wall, side walls, a partition wall between the side walls, a bottom wall, a top platform, a top wall and an inner bottom wall having openings and spaced from the bottom wall, the space above the wall 15 having the openings constituting a burner chamber and the space below the wall having the openings constituting a draft chamber, the top wall which constitutes the upper wall of the burner chamber having openings therethrough, a pair of oil burners supported in the burner chamber, the spaces between the top wall of the burner chamber and the top platform forming an upper heating chamber, and a baffle depending from the top wall of the burner chamber between the oil 20 burners.

2. In a range or stove the combination of a front wall, rear walls, side walls, a partition between the latter, a bottom wall and a top platform, a mounting bracket supported on said bottom wall, a column extending up from the mount- 25

ing bracket, a supporting bracket at the upper end of the column, a pair of oil burners carried by the supporting bracket, supports extending up from the oil burners, an angle shaped supporting ring supported by the supports of each oil burner, the top wall of a burner chamber in the range or stove supported by said rings, and a bottom wall having openings for the burner chamber supported by said column. 5

3. In a range or stove the combination of a 10 burner chamber therein, a top wall for the burner chamber having openings, a bottom wall for the range or stove spaced below the burner chamber, a mounting bracket supported on the latter, a column extending from the mounting bracket, 15 an inner bottom wall having openings supported on said column and spaced from the bottom wall of the range or stove, a supporting bracket at the upper end of the column, a pair of oil burners supported by the latter bracket, a plurality of 20 supports extending up from each oil burner, an angle shaped supporting ring supported by the supports of each burner, the latter supporting the top wall of the burner chamber, a removable hood having an opening supported on each 25 angle shaped supporting ring for the openings in the top wall of the burner chamber and a handle for each removable hood.

HARRY L. GERE. 30
